HENRY G. JANCSY, OF EVERETT, MASSACHUSETTS.

COOLING APPARATUS.

Application filed June 12, 1926. Serial No. 115,416.

The invention relates to a cooling method and apparatus essentially adapted for keeping frozen articles such as ice cream during transportation by truck or wagon.

Efficiency, saving of space and economy are the objective ends desired to be obtained by the invention, the especial object being to provide an efficient and economical cooling system with a simple and compact apparatus without the use of ice and without the use of a refrigerating machine located on the truck or wagon.

As will later be more fully explained in the light of the drawings, the objects of the invention are attained by providing the truck or wagon with a cooling unit within which a liquid refrigerant will circulate. The cooling unit is contained within an insulated casing. The unit comprises a tank of sufficient size to contain a considerable body of the refrigerant. Coupled to this tank is a hollow cooling fixture into and through which the refrigerant will circulate from the tank. This cooling fixture is located in or in cooling relation to a cooling compartment within which the ice cream or article to be cooled is kept and the connection of the fixture with the tank is such that as the temperature of the refrigerant in the fixture exceeds that of the refrigerant in the tank, circulation of the refrigerant will ensue, the warmer refrigerant rising from the fixture and flowing back into the tank and the cooler refrigerant passing from the tank into the fixture, a circulation of the fluid refrigerant being thereby created.

With a cooling unit of the above character installed on the truck or wagon an intensive circulation of the refrigerant cooled to a relatively low temperature is effected from a point outside the wagon. This refrigerant contained in a separate receptacle, is cooled by any of the well known types of refrigerating machine and is circulated through the cooling unit on the truck or wagon by means of a pump. This circulation is continued until such time as the cooling unit and the walls of the insulated compartment in which it is contained are thoroughly cooled, or, in other words, cooled approximately to the low temperature of the refrigerant being circulated through the unit. After such time, the outside means for effecting circulation of the fluid then being cut off, the unit is sealed with the fluid refrigerant left in it sufficient to fill the tank and cooling fixture connecting with

it, space only being left for expansion, and afterward circulation of the refrigerant will continue throughout the unit when the temperature in the fixture exceeds that of the tank in accordance with the constructive principle of the unit as above explained.

Referring now to the drawings:—

Figure 1 is a vertical cross section of the insulated chamber and cooling unit therein as established on the truck or wagon. Shown also in this figure in elevation are parts illustrative of the manner in which a fluid refrigerant may be circulated through the cooling unit from a point outside the truck or wagon.

Fig. 2 is a cross section on the line 2—2 of Fig. 1, and

Fig. 3 is a cross section on the line 3—3 of Fig. 1.

1 represents the insulated casing which surrounds the cooling unit located on the truck or wagon. This casing is preferably rectangular in form with walls made double and insulating material between them. The casing may form a part of the body structure of the vehicle or it may be an independent structure placed within or upon the vehicle body. The casing is also provided with a door 2 through which access is had to the chamber of the casing.

The chamber of the casing is preferably divided into two separate compartments 4 and 5, respectively, one above the other, and separated by a partition 6. The lower of these compartments or the compartment 5 is that in which the articles to be kept cool are placed, access being had to the compartment through the door 2 of the casing.

Located in the upper compartment 4 and resting on the partition 6 is a tank 7 of some considerable size.

Connecting with the tank 7 and located within the lower compartment 5 in surrounding relation to the article or articles placed within it, is a cooling fixture 8. This fixture preferably comprises a number of hollow metal plates or slabs 9. The plates are arranged on end standing in an upright position, resting on the bottom of the casing. The plates are connected at the top and bottom by hollow pipe connections 10.

Extending from the bottom of the tank is a pipe connection 11 which extends into the interior of one of the hollow plates and preferably to a point well down inside it, but terminating at a point removed from the bottom of the plate.

Extending from the top of one of the hollow plates 10 and preferably one of the plates other than that into which the pipe connection 11 is extended, is a pipe connection 12 which connects with the side of the tank at a point just below its top, leaving a space between the point where this connection enters the tank and the top wall of the tank.

Closing an opening 13 in the top of the tank 10 is a plug 14 bearing a cock 15. Access is had to this cock for turning it through an opening 16 in the top wall of the casing, which opening is normally closed by a plug 17.

Extending from the side of the tank to a point outside the casing is a pipe connection 18. This pipe connection at a point outside the casing is provided with a valve 19 for controlling the passage through the pipe. The pipe connection 18 extends from the side of the tank at a point substantially the same distance removed from the top of the tank as is the pipe connection 12. A pipe connection 20, like the pipe connection 18, extends through and outside the casing from one of the plates 10, preferably at a point near the bottom of this plate. The pipe connection 20 outside the casing is provided with a valve 21 for controlling the passage through it.

In order that the cooling unit may be especially effective, it is desired that the tank together with the cooling fixture have such capacity as will contain some considerable quantity of refrigerant. In practice a capacity of 75 gallons has been found to be effective.

Referring now to the charging of the cooling unit: 23 represents a charging tank. This tank is preferably of a size to contain a large quantity of refrigerant or several times the amount of refrigerant required to charge any one cooling unit. Its interior is equipped with coils 24 through which a cooling fluid passed from the refrigerating machine 25, shown diagrammatically. In this connection it will be explained that the charging tank 23 and refrigerating machine 25 are both located at the home station or point where all trucks and wagons equipped with cooling units return and at which point the units are charged.

Extending from the charging tank 23 preferably at a point near the bottom of this tank, is a pipe connection 26 having in it a valve 27. This pipe leads to a pump 28. Beyond the pump the connection between it and the pipe 20 is established by means of a removable flexible connection or hose 29. Extending also from the charging tank preferably at a point near the top of this tank, is a pipe connection 30 having in it a valve 31. Connection is established between this pipe and the pipe 18 by means of a removable pipe connection or hose 32.

The general operation is as follows:—

It will be assumed that a wagon or truck

equipped with a cooling unit is at the station where the refrigerating machine, charging tank and pump are located as permanent fixtures and that communication has been established between the pipes leading from the charging tank and those connecting with the cooling unit by means of the removable flexible connections 29 and 32, all the valves in the several pipes then being opened. The refrigerating machine is then started for cooling the refrigerant in the charging tank and at the same time the pump 28 is set in operation. Thereupon the refrigerant will be circulated through the cooling unit on the truck or wagon, the refrigerant entering by way of the pipe 20 into the cooling fixture 8 and passing out by way of the pipe 18 from the top of the tank 7 and returning to the charging tank. The cooling of the refrigerant and its circulation through the cooling unit is continued until the refrigerant has reached the desired low degree of temperature and also until the cooling unit and the walls of the insulated compartment in which it is contained are thoroughly cooled or cooled approximately to the low temperature of the refrigerant being circulated through the unit. After such time the refrigerating machine and pump are stopped and the valves 21 and 27 closed, leaving the cooling unit filled with the refrigerant. Thereupon the plug 17 is removed from the top of the casing and the cock 15 in the top of the tank 7 opened. This permits a portion of the refrigerant in the tank to flow back into the charging tank by way of the pipe connections 18, 32 and 30 until the refrigerant reaches a point below the inlet of the pipe 18 from the tank, thus establishing the level of the refrigerant left in the tank which is below the top of the tank and leaving a space for permitted expansion of the refrigerant as the temperature changes. The level of the refrigerant in the tank 7 thus being established, the cock 15 is closed, the plug 17 returned to close the opening in the casing and the valve 19 closed, thus sealing the cooling unit and completing its charging. The flexible pipes or hose 29 and 32 are then removed. After this the refrigerant will continue to circulate in the cooling unit for

keeping cool the cooling fixture as long as any cooling efficiency remains in the refrigerant. The efficiency of the cooling unit as a refrigerating medium under ordinary hot weather conditions will continue for some 10 or 12 hours depending upon the temperature to which the refrigerant, the cooling unit and adjacent walls of the insulated compartment have been initially cooled. In this connection it is preferred that they be initially cooled to a temperature of approximately ten degrees below zero.

Any of the well known liquid refrigerants may be used. Of these a mixture of alcohol and water in the proportions of 50 per cent

alcohol to 50 per cent. water have been found to be especially good.

After the cooling unit has lost its efficiency the wagon or truck is then returned to the 5 charging station and the unit recharged, the operation of recharging being carried out the same as before.

To prevent the fluid refrigerant flowing out of the bottom of the tank when the pump is 10 stopped and before the valve 21 is closed, a ball valve 33 is preferably placed in the pipe 29.

Having thus fully described my invention, I claim and desire to secure by Letters Patent of the United States:—

1. A cooling apparatus comprising an insulated casing having within it separate compartments arranged one above the other, a tank for containing a body of refrigerant located in the upper one of said compartments, a cooling fixture arranged in the lower one of the compartments, a pipe connection leading from the bottom of the tank into the cooling fixture, and a pipe connection leading 25 from the cooling fixture back to the tank whereby the refrigerant within said tank will circulate from the tank through the fixture and back through the tank consequent upon thermal changes in the refrigerant, and valve-controlled pipe connections leading from the tank and cooling fixture respectively with extension through the insulated casing whereby a refrigerant may be circulated through said tank and fixture from a point outside 35 said casing.

2. A cooling apparatus comprising an insulated casing having within it separate compartments arranged one above the other, a tank for containing a body of refrigerant lo-

cated in the upper one of said compartments, 40 a cooling fixture arranged in the lower one of the compartments, a pipe connection leading from the bottom of the tank into the cooling fixture, a pipe connection leading from the cooling fixture back to the tank whereby the 45 refrigerant within said tank will circulate from the tank through the fixture and back through the tank consequent upon thermal changes in the refrigerant, and valve-controlled pipe connections leading from the tank 50 and cooling fixture, respectively, with extension through the insulated casing whereby a refrigerant may be circulated through said tank and fixture from a point outside the casing, that one of said valve-controlled connections leading from the tank being arranged in position to determine the level of the refrigerant in said tank.

3. A cooling apparatus comprising an insulated casing having within it a cooling compartment, a cooling fixture arranged inside the casing in cooling relation to said compartment, a tank for containing a body of refrigerant located within the casing above said fixture, pipe connections between the tank and fixture whereby a thermosyphonic circulation will be established between the tank and fixture for refrigerant contained therein, and valve-controlled connections leading from the tank and cooling fixture respectively with extension through the insulated casing whereby a refrigerant may be circulated through said tank and cooling fixture from a point outside said casing and afterward the refrigerant be left in the tank and cooling fixture to circulate therein by thermosyphonic action as aforesaid.

HENRY G. JANCSY.
